A. WHITCRAFT

DIPPER

Filed July 6, 1922

Inventor
Arthur Whitcraft
by James R. Hodder
Attorney

Patented Feb. 6, 1923.

UNITED STATES PATENT OFFICE.

ARTHUR WHITCRAFT, OF BUCYRUS, OHIO.

DIPPER.

Application filed July 6, 1922. Serial No. 573,103.

To all whom it may concern:

Be it known that I, ARTHUR WHITCRAFT, a citizen of the United States, and a resident of Bucyrus, Ohio, have invented an Improvement in Dippers, of which the following description, in connection with the accompanying drawings, is a specification, like letters on the drawings representing like parts.

10 My present invention relates to excavating and dredging machinery, and more particularly to an improved dipper therefor.

The average dipper used in excavating and dredging machinery being built of a plurality of plates riveted together and being subjected to tremendous stresses and strains, in a very short time becomes useless because of the wear of the rivets or the shearing off of such rivets. Such dippers are being continuously repaired and, as it has heretofore been impossible to remove the cause of wear, that is, the strain on the rivets holding the elements of the dipper together, the item of upkeep has been exceedingly high when compared with the initial cost of the dipper. By my present invention, I propose to build a dipper in which the body portion is made up of a front and a back section, each formed from cast metal, preferably cast manganese steel and with two interlocking and connecting side plates or sections so designed as to better join the front and back together and eliminate the usual repairs heretofore necessary. In my invention, when the dipper is lifted by means of a suitable bale or from the back or other connection attached to the body portion, the strains are distributed uniformly through the front section of the dipper. In

40 this connection the location of the bale pin hole with relation to the rivets in the side plates of the body portion and the design of the side plates themselves form an improved joint that prevents rivet shearing and, therefore, the necessity of frequent and extensive repairs. This construction prevents distortion taking place between the front and rear portions of the body such as occurs in the usual construction of such dippers, and the strains due to lifting when digging are distributed and absorbed by the plate.

The principal object of my invention, therefore, is an improved dipper for excavating and dredging machinery.

55 Another object is an improved form of

side plate whereby a better connection between the front and back of the dipper is obtained and shearing of the rivets that hold the various parts together is prevented.

60 Other objects and novel features of the construction and arrangement of parts comprising my improved structure will appear as the description of the invention progresses.

65 In the accompanying drawings:

Fig. 1 is a side view;

Fig. 2 is a plan view;

Fig. 3 is a partial front elevation of 70 Fig. 1;

Fig. 4 is a horizontal section on the line 4-4 of Fig. 1;

Fig. 5 is a section on the line 5-5 of Fig. 1, and

Fig. 6 is a section on the line 6-6 of 75 Fig. 1.

Referring to the drawings, 10 designates a back plate provided with a plurality of eyes 11 for attaching lifting devices to the dipper and with a plurality of bearing blocks 80, 12 in which are rotatably mounted shafts 13 to which are secured brackets 14 that carry the bottom plate 15. Abutting against the forward edge of the back plate 10 is a curved front plate 16 provided on each side on the 85 front portion adjacent the abutting edge, above referred to, with a channel 17 in which fits a plate 18, this plate being securely fastened to the front by a plurality of rivets 19 and provided at its upper end with a bale pin 90 hole 20, the bale pin holes 20 of the plates 18 being in alignment with each other, as shown in Fig. 2.

Only the upper rear edge of the front plate and the upper front edge of the rear plate abut, as may be seen in dotted lines in Fig. 1, and the lower portion of such edges are cut away to form a substantially elongated rectangular space in which fits snugly the inwardly projecting portion 21 of the 100 side plate 22, as shown in cross section in Fig. 4. The upper end of the side plate 22 fits snugly into a recess 23 cut in the rear and front plates 10 and 16, respectively, as shown in Fig. 6, the front and rear plates 105 and side plate being securely fastened together by a plurality of rivets 24. That portion of the cut away portion 23 for the reception of the top end of the side plate 22 in the rear plate 10 forms a projecting 110 lug 25 on such back plate, and this lug may be of various lengths and sized according to

the capacity of the dipper and is designed to bring a bearing surface on the side plates. The form of the front plate in advance of the passage or channel 17 is such as to distribute the metal to make the strains of pulling more uniform than has heretofore been possible throughout the body portion of this section. That portion 21 of the side plate 22 forms a joint between the front and back 10 body portions and prevents strains from being directly applied to the rivets 24, and the shape of such plate gives the interior of the dipper a smooth surface and makes a complete connection between the various parts 15 of the dipper body.

While I have shown and described the preferred embodiment of my invention somewhat in detail, it is to be understood that I may vary the details of the arrangement and construction of parts comprising my improved structure without departing from the spirit of the invention.

Having thus described my invention, what I claim as new is:

- 25 1. In an improved dipper for excavating and dredging machinery, the combination of a back plate, a front plate, the rear edge of the said front plate abutting against the front edge of the rear plate, a side plate 30 associated with the front and back plates and securely riveted thereto, and a portion of said side plate extending between the front and back plates whereby the rivets are freed from strain while the dipper is in use.
- 35 2. In an improved dipper for excavating and dredging machinery, the combination of a back plate, forwardly extending members formed on said back plate and at each side thereof, a curved front plate having rearwardly extending portions at each side thereof, the upper end of the forwardly extending portions of the back plate and the rearwardly extending portions of the front plate abutting and with the lower end of

said portions cut away to form a recess, a 45 channel formed in the upper portion of said forwardly and rearwardly extending portions, a side plate having its upper end formed into said channel, and the lower central interior side of said side plate formed 50 to fit in the said recess, a plurality of rivets for securing the side plate to the back and front plates, a channel formed in the rearwardly extending portions of the front plate, and lugs fitting into said last named 55 channel and secured to the front plates.

3. In an improved dipper for excavating and dredging machinery, the combination of a body comprised of back and front plates having forward and rearward extending portions respectively abutting, side plates riveted to the forwardly and rearwardly extending portions, a lug on the back plate engaging the side plates to form a bearing therefor whereby a pull on the 65 front section during the use of the dipper is distributed throughout the front plate.

4. In an improved dipper for excavating and dredging machinery, the combination of front and back sections abutting each 70 other, a single channel formed in the top side of the front and back sections, and a side plate fitting into said channel and riveted to the front and back sections to form an outside lock bearing for the dipper. 75

5. In an improved dipper for excavating and dredging machinery, the combination of front and back sections abutting at their top sides and cut away on the lower side to form a recess, a side plate riveted to, and 80 securing the front and back sections together, and an inwardly extending member on the side plate fitting into said recess and forming an inside lock bearing for the dipper. 8

In testimony whereof, I have signed my name to this specification.

ARTHUR WHITCRAFT,
